United States Patent Office

Des. 213,970
Patented Apr. 29, 1969

213,970

ANTENNA SPINNER

Donald J. Mayhew, 1319 Saxony Lane,
Houston, Tex. 77058

Filed Dec. 28, 1967, Ser. No. 9,964

Term of patent 14 years

Int. Cl. D12—14; D21—04

U.S. Cl. D29—1

FIG. 3

FIG. 2

FIG. 1

FIG. 4

FIG. 7

FIG. 6

FIG. 5

FIG. 8

FIGURE 1 is a perspective view of an antenna spinner showing one embodiment of my new design.

FIGURE 2 is a side elevation view of the embodiment of my new design shown in FIGURE 1.

FIGURE 3 is a top plan view thereof.

FIGURE 4 is a bottom plan view thereof.

FIGURE 5 is a perspective view of an antenna spinner showing a second embodiment of my new design.

FIGURE 6 is a side elevation view of the second embodiment of my new design.

FIGURE 7 is a top plan view thereof.

FIGURE 8 is a bottom plan view thereof.

The faces of the antenna spinner not shown are substantially the same in appearance as the faces shown.

I claim:

The ornamental design for an antenna spinner, as shown and described.
